UNITED STATES PATENT OFFICE.

JAMES M. RICE, OF LINEVILLE, ALABAMA.

MACHINE FOR DRESSING STONE.

1,396,144.

Specification of Letters Patent.

Patented Nov. 8, 1921.

Application filed May 1, 1920. Serial No. 378,196.

To all whom it may concern:

Be it known that I, JAMES M. RICE, a citizen of the United States, residing at Lineville, in the county of Clay and State 5 of Alabama, have invented certain new and useful Improvements in Machines for Dressing Stone, of which the following is a specification, reference being had to the accompanying drawings.

10 This invention relates to certain improvements in machines for dressing stone and has relation more particularly to a machine of this general character especially designed and adapted for use in connection with millstones, and it is an object of the invention to provide a novel and improved device of this general character which may be employed to resurface or dress a millstone, or the like, without the necessity of removing such 15 stone from working or applied position.

It is also an object of the invention to provide a novel and improved machine of this general character including an impact tool and wherein mechanism is employed 20 for operating said tool with the mounting for the stone serving as a driving element.

Another object of the invention is to provide a novel and improved machine of this general character embodying a pickax, together 25 with means for imparting the requisite strokes or impulses to the pickax and wherein said pickax is of a type whereby the same may be reversed so that the life of the same is materially prolonged.

30 An additional object of the invention is to provide a novel and improved machine of this general character which may be employed with equal facility in connection with a millstone, or the like, revolving about 35 either a horizontal or vertical axis.

Furthermore, it is an object of the invention to provide a machine of this general character with novel and improved means whereby the stroke of the working tool 40 may be readily regulated, together with means whereby the angle of the working edge of the tool with respect to the surface of the stone may be varied as required.

The invention consists in the details of 45 construction and in the combination and arrangement of the several parts of my improved machine whereby certain important advantages are attained and the device rendered simpler, less expensive and otherwise 50 more convenient and advantageous for use, as will be hereinafter more fully set forth,

The novel features of my invention will hereinafter be definitely claimed.

In order that my invention may be the better understood, I will now proceed to describe the same with reference to the accompanying drawings, wherein:

Figure 1 is a view partly in elevation and partly in section, illustrating a machine constructed in accordance with an embodiment 65 of my invention;

Fig. 2 is an enlarged fragmentary view partly in top plan and partly in section, illustrating certain details of construction as herein embodied;

Fig. 3 is a fragmentary view partly in section and partly in side elevation, illustrating in detail means for reciprocating the tool carrying rod and for imparting axial rotation thereto;

Fig. 4 is a fragmentary view partly in elevation and partly in section of the lower portion of the structure illustrated in Fig. 3 and substantially at right angles thereto;

Fig. 5 is a sectional view taken substantially on the line 5—5 of Fig. 3;

Fig. 6 is a fragmentary view in end elevation, illustrating in detail the means for intermittently rotating the threaded shaft;

Fig. 7 is a view in side elevation, illustrating a machine constructed in accordance with an embodiment of my invention and mounted for use in connection with the stones supported by a horizontally disposed 90 spindle; and

Fig. 8 is a fragmentary view in elevation of the structure as illustrated in Fig. 7.

As disclosed in the accompanying drawings, M denotes a millstone mounted upon the vertically disposed spindle S and which spindle is adapted to be driven in any desired manner whereby the millstone rotates around a vertical axis. 1 denotes a coupling adapted to be clamped to the upper end portion of the spindle S through the instrumentality of the screw 2, or the like. Also extending within the coupling 1 is an end portion of an elongated shaft 3 which is secured to the coupling 1 for rotation therewith by the screw 4, or the like. F denotes a frame embodying a side member 5 and the end members 6 and 7. The member 6 constitutes a barrel or sleeve loosely mounted upon the shaft 3 whereby said shaft is capable of rotary movement independently of the frame F. The end portions of the members 6 and

7 remote from the side member 5 rotatably support a shaft 8 substantially in parallelism with the side member 5. Locked to the shaft 8 at a point in close proximity to the end 5 member or sleeve 6 is a friction wheel 9 in driven contact with the friction wheel 10 locked to the shaft 3. By this arrangement, as the shaft 3 rotates, the shaft 8 will also be caused to revolve.

10 Rotatably supported by the end members 6 and 7 at a desired point between the side member 5 and the shaft 8 is a threaded shaft 11. One end portion of the shaft 11 extends outwardly of the end member 7 and 15 secured to said extended portion is a feeding gear or ratchet 12 adapted to be intermittently rotated by the lever or pawl 14 engaging said gear or ratchet. The outer end portion of the lever or pawl 14 is pivotally engaged with a rod 15. One end portion of the rod 15 is operatively engaged with a wrist pin 16 carried by a disk 17, or the like, fixed to an ended end portion of the shaft 8. The opposite end portion of the 20 rod 15 is slidably disposed through a guide bracket 18 mounted upon the end of the member 7 remote from the shaft 8. As the shaft 8 rotates, the rod 15 will be reciprocated causing the pawl or lever 14 to intermittently engage the gear or ratchet 12, 25 resulting in an intermittent rotation of the shaft 11. The working end of the pawl or lever 14 engages the gear or ratchet 12 to one side of its center and by throwing said 30 gear or ratchet 12 to either side, the shaft 11 may be caused to rotate in the direction desired.

The wrist pin 16 is adjustable radially of the disk 17 so that the stroke of the rod 15 40 may be adjusted to regulate or vary, as may be desired, the extent of rotation of the shaft 11 upon the working stroke of the rod 15. In the present embodiment of my invention, the adjustment of the wrist pin 16 is accomplished by having said pin slidably engage 45 within a radially disposed slot 19 and held in desired position by a clamping member 20.

C denotes a cylinder disposed substantially in parallelism with the end members 50 6 and 7 and which is provided at its central portion with an outstanding block 21 threaded upon the shaft 11 so that as said shaft 11 is intermittently rotated, the cylinder C will be caused to move longitudinally thereof and in a direction radially of the millstone M so that the surface of such stone may be properly dressed. Snugly fitting within the cylinder C and having reciprocatory movement therein is a second 55 cylinder 22. The cylinder 22 is provided with an outstanding lug 23 which extends through a longitudinally disposed slot 24 in the adjacent wall of the cylinder C. The opposite end portions of the cylinder C have 60 coacting therewith the cuffs 25 slidably en-

gaged with the side member 5 and with the shaft 8 whereby further means are provided for maintaining the cylinder C in applied position with respect to the frame F. Keyed to the shaft 8 for rotation therewith 70 but capable of movement longitudinally thereof is an eccentric 26 which is constantly in proper position with respect to the lug 23 and said eccentric comprises two 75 reversely directed arcuate arms 27 disposed on desired curvatures and having their inner ends secured to the hub portion of the eccentric 26 at opposite sides of the axial center thereof. The eccentric 26 is caused to move along the shaft 8 in the same general 80 direction as the movement of the cylinder C by the adjacent portion of the cylinder C and the side member of the adjacent cuff 25 between which the eccentric 26 is positioned.

28 denotes an elongated rod extending axially of the cylinder C freely disposed through the opposite ends or heads 29 thereof so that said rod is capable of reciprocatory movement. The rod 28 also extends axially through the cylinder 22 and is secured to the heads 30 thereof for reciprocatory movement therewith but capable of independent rotary movement. In threaded engagement with the outer head or end 95 29 of the cylinder C is a tubular stem 31 into which the adjacent end portion of the rod 28 telescopes and the inner end of said stem contacts with a disk 32 loosely mounted upon the portion of the rod 28 100 within the cylinder C. Interposed between the disk 32 and the adjacent or outer head 30 of the cylinder 22 is a coil spring 33 encircling the rod 28. The spring 33 constantly urges the cylinder 22 in one direction and the tension of said spring may be varied by rotating the stem 31. The outer end of the stem 31 is provided with a hand wheel 34 to facilitate the requisite rotation of said stem.

An opposite end portion of the rod 28 extends a material distance outwardly of the inner end of the cylinder C and has secured to its end portion a tool holder 35 substantially in the form of an inverted L. The stem 36 of the holder 35 is provided with a 110 plurality of longitudinally spaced openings 37 whereby the clamping screw 38 may be adjustably engaged therewith so that a corresponding adjustment may be had with the tool or pickax 39. The tool or pickax 39 115 includes the oppositely disposed points 40 so that said tool may be reversed when required in order that the life of the tool or pickax may be materially prolonged.

As the shaft 8 rotates, the eccentric 26 120 forces the cylinder 22 and the parts carried thereby in a direction away from the work or millstone M by contact of the arms 27 with the lug 23. The desired working strokes or impulses are imparted to the cyl- 125 130

inder 22 by the spring 33 as the arms 27 pass the lug 28.

In order to regulate the length of the stroke of the cylinder 22 or more particularly the rod 28 and the tool 39 carried thereby, I provide the rod 28 at a predetermined point beyond the inner head or end 29 with a fixed collar 43. The lower cuff 25 and the cylinder C are provided with a pair of brackets 44 spaced longitudinally of the cylinder C and which rotatably support a threaded shaft 45 provided at its outer end with an operating head or end wheel 46 whereby the shaft may be readily rotated. The bracket 44 carried by the cuff 25 also serves as a guide for an elongated arm 47 disposed substantially in parallelism with the rod 28. The arm 47 outwardly of said bracket 44 is provided with a pair of longitudinally spaced lugs 48 operatively engaged with the threaded shaft 45 whereby said arm 47 may be moved longitudinally in the direction desired upon requisite rotation of the shaft 45.

The arm 47 at its forward end is provided with a lateral extension 49 substantially at right angles thereto and positioned outwardly of the collar 43. The rod 28 moves freely through the outer end portion of the extension 49 whereby said extension 49 serves as a stop coacting with the collar 43 to limit the extent of movement of the rod 28 under the influence of the spring 33. By moving the extension 49 in a direction away from the collar 43, the stroke of the rod 28 will be lengthened and upon movement of the extension 49 toward the collar 43, said stroke will be shortened.

It is also of advantage to rock the rods 28 in order to change the angle of the cutting edge of the tool 39. In the present embodiment of my invention, this adjustment is accomplished through the instrumentality of the handle or lever 50 having one end portion extending through a transversely disposed slot 51 in a wall of the cylinder C and through a relatively large opening 52 in the adjacent wall of the cylinder 22 and secured to the rod 28. The angle of the cutting edge of the tool 39 may be changed as required by imparting the requisite swinging movement to the handle or lever 50. The opening 52 is of such length whereby no obstruction or hindrance is offered to the requisite reciprocatory movement of the cylinder 22 and also of requisite width for the same purpose. It is also desired that the inserted end of the handle or lever 50 be loosely engaged with the rod 28 and this is accomplished by providing the rod 28 with an angular portion 53 of desired length and with which the inserted end portion of the handle or lever 50 is engaged and in a manner whereby the rod 28 is capable of endwise movement independently of said

handle or lever 50 but rotated or rocked upon swinging movement of said handle or lever 50.

In Figs. 7 and 8, I disclose an embodiment of my invention wherein a machine is adapted to dress the millstone M', or the like, rotating about a horizontal axis. In this arrangement, the machine is constructed in the same manner as hereinbefore set forth except that the side member or sleeve 5' 75 is mounted upon a horizontally disposed shaft 54 rotatably supported by a supporting structure or frame A. One end portion of the shaft 54 has coupled thereto a drum or pulley 55 in driving connection with the 80 spindle S' of the millstone M', or the like, by the belt 56.

From the foregoing description, it is thought to be obvious that a machine constructed in accordance with my invention is particularly well adapted for use by reason of the convenience and facility with which it may be assembled and operated, and it will also be obvious that my invention is susceptible of some change and modification 90 without departing from the principles and spirit thereof, and for this reason I do not wish to be understood as limiting myself to the precise arrangement and formation of the several parts herein shown in carrying 95 out my invention in practice except as hereinafter claimed.

I claim:—

1. A machine for dressing stone comprising, in combination, a supporting structure, 100 a tubular member supported thereby, a hollow member arranged within the tubular member for reciprocatory movement, the wall of the hollow member being provided with a longitudinally disposed slot, an outstanding lug carried by the hollow member and extending through the slot of the tubular member, a rotatable cam element arranged for contact with the lug to intermittently move the hollow member in one direction, means for rotating the cam member, 105 means for constantly urging the hollow member in the opposite direction, a rod extending through both the tubular member and the hollow member, means for connecting the hollow member and the rod for unitary reciprocatory movement, a stone working tool carried by the rod, and means operatively engaged with the rod at a point within the hollow member for rotating said 110 rod independently of its reciprocation.

2. A machine for dressing stone comprising, in combination, a supporting structure, a tubular member supported thereby, a hollow member arranged within the tubular 125 member for reciprocatory movement, the wall of the hollow member being provided with a longitudinally disposed slot, an outstanding lug carried by the hollow member and extending through the slot of the tubu- 130

lar member, a rotatable cam element arranged for contact with the lug to intermittently move the hollow member in one direction, means for rotating the cam member, 5 means for constantly urging the hollow member in the opposite direction, a rod extending through both the tubular member and the hollow member, means for connecting the hollow member and the rod for unitary reciprocatory movement, a stone working tool carried by the rod, a wall of the tubular member being provided with a transversely disposed slot, the adjacent wall of the hollow member being provided with an 10 opening, said opening being both relatively wide and long, the rod having rotation independently of the hollow member, and an arm extending through the slot of the tubular member and the opening of the hollow 15 member and the inserted end of the arm having sliding connection with the rod, said arm providing means to independently rotate the rod, the sliding connection between the arm and rod permitting the rod to reciprocate independently of the arm.

3. A machine for dressing stone, comprising, in combination, a supporting structure, a tubular member carried thereby and having its opposite end portions closed, a hollow member mounted within the tubular member for reciprocation therein, said hollow member having its opposite end portions closed, a rod extending through the tubular member for reciprocation, said rod also extending through the hollow member, means carried by the rod and coacting with the hollow member whereby said hollow member and rod reciprocate in unison and permitting the rod to have rotation independently 30 of the hollow member, means within the tubular member and engaging an end of the hollow member for constantly urging the hollow member in one direction, driven

means for independently moving the hollow member in the opposite direction, a tool carried by an extended end portion of the rod, and means for rotating the rod independently of the hollow member.

4. A machine for dressing stone comprising, in combination, a supporting structure, a tubular member carried by said supporting structure, a rod operatively supported by the tubular member for reciprocation, means for reciprocating said rod, a threaded shaft rotatably supported by the member, an elongated arm provided with lugs operatively engaged with the threaded shaft, a lateral extension carried by the arm and through which an end portion of the rod is freely disposed, and a collar carried by the rod inwardly of the extension of the arm, said collar contacting with the extension of the arm to limit the extent of movement of the rod in one direction.

5. A machine for dressing stone comprising, in combination, a supporting structure, a tubular member carried by said supporting structure, a rod operatively supported by the tubular member for reciprocation, means for reciprocating said rod, a threaded shaft rotatably supported by the member, an elongated arm provided with lugs operatively engaged with the threaded shaft, a lateral extension carried by the arm and through which an end portion of the rod is freely disposed, a collar carried by the rod inwardly of the extension of the arm, said collar contacting with the extension of the arm to limit the extent of movement of the rod in one direction, and means for rotating the shaft to move the arm to vary the position of the lateral extension of the arm with respect to the collar carried by the rod.

In testimony whereof I hereunto affix my signature.

JAMES M. RICE.
